Atggs.

UNITED STATES PATENT OFFICE

CHARLES Q. IVES, OF STRATFORD, CONNECTICUT, ASSIGNOR TO BROWN COMPANY, OF BERLIN, NEW HAMPSHIRE, A CORPORATION OF MAINE

APPARATUS FOR RAISING LIQUIDS

Application filed October 18, 1926. Serial No. 142,172.

This invention relates to valveless pumps of the type described in the patent to Browne, No. 1,154,745, issued September 28, 1915, by which "slugs" of a fluid are lifted by a difference of pressures at the supply and discharge ends to a height greater than that to which such pressure difference could raise a solid column of the fluid, the slugs of each fluid being well defined and of substantially uniform length. An object of the invention is to provide a slug-forming chamber of such a shape as to enable the pump to work more effectively than the simple U-tube shown in the patent. The advantageous features of my device will appear more fully in the following description and on the drawing, of which

Figure 1 is a diagrammatic view of a certain type of installation of the pump. 20 Figure 2 is a plan of the slug-forming member which constitutes an embodiment of my invention.

Figure 3 is a vertical section of the slug-forming member taken on the line 3—3 of Figure 2.

Figures 4, 5, 6, 7 and 8 are horizontal sections taken on the lines 4—4, 5—5, 6—6, 7—7 and 8—8 of Figure 3.

Referring to Figure 3, the slug-forming member consists of a hollow shell 10 enclosing a chamber having a lower bowl-like portion 11 and an upper portion which is divided into two branches 12, 13, by a baffle or a dam 14 which extends downwardly from the top of the shell 10. A port 15 opens downwardly through the bottom of the shell from the lower portion of the chamber 11 and in the top of the shell, ports 16, 17 open respectively from the branches 12, 13 of the upper portion of the chamber. The dam 14 may be extended downwardly as far as desired. As shown in Figure 3, it extends slightly below the midpoint of the chamber and terminates in a bead 18 which extends horizontally across the chamber from one side to the other and may be substantially cylindrical as shown. The lower extremity 19 of the dam 14 is thus in a horizontal line extending across the chamber. The branch 13 is preferably formed to have a volume

substantially equal to the lower portion 11 of the chamber. As will be seen from the sections indicated in Figures 4, 5, 6 and 7, the cross sectional area of this branch diminishes upwardly so that a Venturi effect is thus produced. 55

The principle of operation of this pump is identical with that described in the patent to Browne above mentioned and may be briefly stated as follows: 60

Taking, for example, air and water as the fluids used, air is admitted through the port 16 and flows around the dam 14 and upwardly through the eduction port 17. During this flow of air, water rises through the port 15 and fills the lower portion 11 of the interior of the member 10. When the level of the water reaches the lower extremity 19 of the dam 14 the flow of air from the branch 12 into the branch 13 is sealed off by the water. 70

In the operation of the pump, the average pressure maintained at the port 16 is slightly greater than that at the port 15, the pressures at both these ports being considerably greater than that at 17. Hence when the air flow is 75 sealed off by the water, the downward pressure of the air through the port 16 and the upward pressure of the water through the port 15 combine to sweep the greater part

of the water which has collected in the chamber 11 up into the branch 13, whence it passes on upwardly through the port 17, impelled by the flow of air which is resumed for an interval during which the level of the water in the chamber 13 again rises to the sealing point. 80

The proper relative pressures at the three ports 15, 16, 17 may be maintained by either the so-called "vacuum" or the "pressure" type of installation. In Figure 1 the former is illustrated diagrammatically. The

slug-forming member 10 is placed so that the level of the liquid to be raised is slightly below the extremity 19 of the dam 14, which may be called the sealing line. The port 15 may open directly into the body of the liquid to be raised but for purposes of regulation I prefer to connect therewith a suitable gate valve 20 to control the flow of liquid. The port 16 may be left open to the atmosphere or may be connected with a regulating gate 100

valve 21. While the apparatus is capable of raising any fluid by the use of a lighter fluid, provided the two are practically immiscible, in most cases the apparatus will be used to raise a liquid of some kind with air. For the purpose of simplicity in describing the apparatus, the two fluids are herein referred to as water and air, although it is to be understood that the apparatus is adapted for use with various other kinds of fluids.

Connected to the port 17 is an eductor pipe 22 which leads up in as vertical a direction as possible to a suitable discharge tank 23. The action of the member 10 is to cause the formation of alternate slugs of water and air at the lower end of the eductor pipe 22. These slugs under proper operating conditions maintain their identity during their travel upwardly through the pipe. As the air and water are discharged into the tank 23, they separate, the water falling into the bottom of the tank and the air rising to the top and passing around suitable baffle plates 24 to a suction pipe 25 which leads to a suitable vacuum pump. The water which is discharged into the tank 23 passes downwardly through a pipe 26 to a water seal 27 whence it is discharged through a pipe 28. The pipe 26 must be long enough to provide a sufficient head of water to counteract the vacuum produced in the chamber 23 by the vacuum pump.

The introduction of the valve 20 on the intake line does not detract from the advantages of the "valveless" pump since this can be and preferably is a rugged gate valve, the only function of which is to regulate the rate of flow of water into the member 10. By regulating the flow through the intake pipe in conjunction with the flow of air through the valve 21, a maximum discharge of water through the pump may easily be obtained for any given working conditions. By selecting just the right size of intake pipe for a given installation, the valve 20 could be dispensed with, but even with its use there is no working part to move during the operation of the pump which can be caught open or clogged by sediment or the like to interfere with the operation of the pump.

The slug-forming member 10 may be also used in a "pressure" installation in which the eductor pipe 22 discharges to the atmosphere, whereas a pressure higher than atmosphere is supplied through the port 16 and the water to be raised is supplied through the port 15, preferably by a suitable head, at a pressure only slightly below that of the air supply. The member 10 formed as described and illustrated has proven to be considerably more effective in operation than the U-bend shown in the Browne patent, this difference of effectiveness being considerably more marked in the vacuum installation as shown in Figure 1 than in the pressure installation.

Among the distinguishing features of construction of the member 10 which may account for its superior action is the straight horizontal lower extremity of the dam 19 which results in a more rapid sealing off of the air flow from the branch 12 to the branch 13 when the level of the water rises to the level of the extremity 19. The enlarged capacity of the lower portion 11 of the chamber also provides a greater body of water quickly available for the formation of the slug in the eductor pipe. When the rise of water in the chamber 11 seals off the air entering through the port 16, a greater portion of the water in the chamber 11 is at once swept up into the branch 13 which is of substantially the same capacity as that of the chamber 11. By reason of its diminishing cross section, the slug of water received therein increases in velocity as it travels upwardly into the eductor pipe 22. The combined effects of the quick sealing off of the descending air in the branch 12 and the comparatively large body of water in the chamber 11 which is at once swept up into the branch 13, together with the increase of velocity caused by the Venturi effect in the chamber 13, is responsible for a very marked increase in effectiveness of the member 10 over a simple U-bend.

Having thus described an embodiment of my invention, it should be evident to those skilled in the art that various changes and modifications may be made therein without departing from its spirit or scope as defined by the appended claims.

I claim:

1. A device of the class described, comprising a hollow, normally upright shell enclosing a chamber, and a transverse dam within the shell extending downwardly from the top thereof, said dam comprising a comparatively thin wall terminating at its lower end in a horizontally disposed enlarged head portion extending from one side of said chamber to the other, said dam also dividing the upper portion of said chamber into two separate branches, said shell having ports therethrough opening from the bottom of said chamber and from the top of the two branches thereof.

2. A device of the class described, comprising a hollow, normally upright shell, and a transverse dam extending downwardly within said shell from the top thereof, said shell enclosing a chamber having a lower portion and two upwardly extending branches separated by said dam, one of said branches having a volume substantially equal to that of the lower portion of the chamber, and having an upwardly decreasing cross sectional area, said shell having ports therethrough opening from the bottom of said chamber and from the top of the two branches thereof.

3. A device of the class described, comprising a member having a chamber therein, and a dam extending downwardly into said chamber from the top thereof dividing the upper portion thereof into two separate branches,
5 one of said branches having a volume substantially equal to that of the lower portion of said chamber below said dam and an upwardly decreasing cross sectional area, said dam terminating at its lower end in a rounded
10 horizontal portion extending across said chamber, said member also being provided with ports opening out from the lower end of the chamber and from the top of each branch of the upper portion.
15 4. A device of the class described, comprising a hollow, normally upright shell enclosing a bowl-like chamber in its lower portion, said shell having a transverse dam extending downwardly from the upper end thereof and
20 forming with said shell two passages immediately above said chamber, said dam being formed at its lower extremity with a horizontally disposed cylindrical bead, said shell also being provided with ports communicating
25 with said passages through the upper end thereof and with said chamber through the lower end thereof.

In testimony whereof I have affixed my
signature.
